UNITED STATES PATENT OFFICE.

FREDERICK W. CAPPELEN, OF MINNEAPOLIS, MINNESOTA, ASSIGNOR TO DECARIE INCINERATOR COMPANY, OF HOPKINS, MINNESOTA, A CORPORATION OF MINNESOTA.

INCINERATOR.

1,110,888.

Specification of Letters Patent. Patented Sept. 15, 1914.

Application filed March 24, 1911. Serial No. 316,763.

To all whom it may concern:

Be it known that I, FREDERICK W. CAPPELEN, of Minneapolis, Hennepin county, Minnesota, have invented certain new and useful Improvements in Incinerators, of which the following is a specification.

The object of my invention is to provide an incinerator having an improved form of grate which will allow the flames to circulate around the mass of garbage on the grate and will also prevent the load on the grate from clogging and choking up the middle portion of the grate.

A further object is to enlarge the surface exposed to the action of the flames.

The invention consists generally in a grate having a centrally arranged header, and grate bars or tubes depending therefrom and diverging outwardly to the walls of the combustion chamber.

Further the invention consists in upright bars or tubes connecting the diverging bars with the top of the combustion chamber and spaced from the side walls thereof.

In the accompanying drawings forming part of this specification, Figure 1 is a vertical sectional view of an incinerator embodying my invention, Fig. 2 is a vertical sectional view taken on a section line at right angles substantially to the section line of Fig. 1, Fig. 3 is a vertical sectional view through the paper burning chamber of the incinerator.

In the drawing, 2 represents the combustion chamber of the incinerator, having a grate 3, a water space 4 in its walls, and with a chamber 5 forming the top of said combustion chamber. A hopper opening 6 is provided through the top of the combustion chamber having covers 7 flush with the floor 8, and beneath the covers are doors 9, which swing downward under the weight of the material deposited therein. A space 10 is provided beneath the floor 8, extending over and around the top of the combustion chamber. A flue opening 11 is formed in the wall of the combustion chamber leading to a chamber 12 wherein a wall 13 of fire-brick is provided, the brick being so arranged that passages will be formed between them through which the products of combustion will pass to the stack. The brick will become incandescent and will consume a large proportion of the gases in the prod-

ucts of combustion. Pipes 14 connect the chamber 5 with the water space in the wall of the combustion chamber on one side and extend across the opening 11 and prevent any of the material from lodging in this opening and being carried into the chamber 12. 15 is a header consisting of a pipe communicating at each end with the water space 4 in the walls of the combustion chamber and extending lengthwise of said combustion chamber and preferably in a central position with respect to the same. A series of pipes or tubes 16 are connected to the lower walls of the header 15 and depend therefrom and are provided with horizontal portions 17 which extend outwardly, parallel, substantially, with the grate 3 and communicating with the water space in the walls of the combustion chamber. Pipes 18 connect the outer ends of the horizontal portions 17 with the chamber 5 and are preferably substantially parallel with the walls of the combustion chamber and are spaced a sufficient distance therefrom to allow circulation of the hot air and gases on both sides of the garbage supporting grate, so that the flames can pass between this material and the walls of the combustion chamber and assist materially in drying the mass on the grate rendering its combustion more rapid and complete. The centrally arranged header will have the effect of separating the material as it falls from the hopper and prevent it from accumulating and packing down in the middle of the grate. Furthermore, this header being raised above the horizontal portions of the grate, the flames will pass between the diverging portions of the bars 17 and will expose a greater portion of the material to the action of the flames than would be possible if the horizontal portions extended entirely across the combustion chamber. In other words, the raised central portion of the grate has the effect of separating the material and throwing it out toward the sides of the combustion chamber and thereby hastening the drying and insuring a more rapid combustion of the material. Contact of the material with the walls of the combustion chamber is prevented by the upright pipes 18. The water circulating through the header 15 and the tubes leading therefrom will become heated and the steam from the chamber 5

may be drawn off for commercial purposes through a means which I have not thought necessary to illustrate herein.

The paper combustion chamber forms the subject-matter of a separate application Serial No. 616,764, filed March 24, 1911, and need not be referred to except to state that it consists of a chamber 19 having a cover 20, a fuel grate 21, a paper supporting grate 22 and an opening 23 leading to the chamber 2. A fuel opening 24 is also provided in the wall between the chambers 2 and 19 on a level substantially with the grates and opposite the stoking hole 25. A similar stoking hole 26 is preferably provided opposite the grate 22.

I claim as my invention:—

1. The combination, in an incinerator with a combustion chamber formed with a water space in its walls, of a header consisting of a pipe communicating at its ends with the water space in the opposite walls of the combustion chamber, tubular grate bars extending outwardly from said header and communicating with said water space, and means preventing contact of the material with the walls of said chamber.

2. The combination, in an incinerator having a fuel grate and a filling opening, of a grate for the refuse material having substantially horizontal side portions and a raised central portion, said raised central portion dividing the material deposited through said filling opening and directing it upon said side portions, and means preventing contact of the material with the walls of said incinerator.

3. The combination, in an incinerator, with a combustion chamber, having water spaces in its walls, of a fuel grate and a filling opening, a garbage grate arranged above said fuel grate and consisting of a centrally arranged header, tubular grate bars extending outwardly therefrom and forming a circulating means between said water spaces and said header and vertical tubes connecting the outer portions of said outwardly extending tubular grate bars with the top of said combustion chamber, and preventing contact of the material with the walls of said combustion chamber.

4. The combination, in an incinerator with a combustion chamber having a fuel grate and a filling opening and a water space, of a garbage grate arranged above said fuel grate and comprising a water circulating header extending across said combustion chamber, water circulating tubes extending from said header to said water space, a portion of said tubes preventing contact of the material with the walls of said chamber.

5. The combination, in an incinerator having a fuel grate and a filling opening and circulating chambers, of a header extending across the combustion chamber of said in-

cinerator beneath said filling opening and having its ends communicating with said circulating chambers, pipes depending from said header and having outwardly extending, horizontal portions also communicating with circulating chambers in the walls of said incinerator, said header operating to divide the material falling thereon and direct it outwardly upon the horizontal portions of said pipes and means preventing the material falling on the horizontal portions of said pipes from contacting with the walls of said incinerator.

6. The combination, in an incinerator with a combustion chamber formed with a circulating space in its walls and a grate provided in the lower portion of said chamber, of a header comprising a pipe arranged midway substantially of said combustion chamber above said grate and having its ends communicating with the circulating chamber in the walls of said incinerator, tubular grate bars having their inner ends connected to said header and depending therefrom, the middle and outer portions of said tubular grate bars being horizontal, substantially, and communicating with the circulating space in the walls of said incinerator above the stoking holes for said grate, and means communicating with said tubular grate bars near said water circulating space and with the space in the top of said combustion chamber, said bars and said means supporting the garbage material out of contact with the walls of said chamber.

7. The combination, in an incinerator with a combustion chamber having water spaces in its walls, of a header centrally arranged in said combustion chamber and communicating at its ends with the water space in the opposite walls thereof, tubular grate bars extending from said header to the water space on opposite sides thereof, and circulating tubes connected to the upper portion of said combustion chamber and communicating with said tubular grate bars and preventing the contact of the material with the walls of said chamber.

8. The combination, in an incinerator having a combustion chamber, of an incinerating grate comprising a centrally arranged header, water-circulating tubes extending from said header, said header being raised above the level of the outer portion of said tubes to direct the material outwardly toward the walls of said combustion chamber, and means preventing contact of the material with the walls of said chamber.

9. The combination, in an incinerator with a fire-grate and a combustion chamber formed with a water space in its walls, of a header comprising a pipe extending across said combustion chamber below the middle portion of said chamber adjacent to said fire-grate and communicating at its ends with

said water space, a series of tubular grate bars communicating at their outer ends with said water space and extending horizontally into said combustion chamber on each side of said header to a point near the middle portion of said chamber, the inner ends of said bars being upwardly turned and communicating with said header, the outer portions of said bars presenting substantially flat 10 surfaces on each side of said header upon

which the material is directed by said header and the upwardly turned inner ends of said bars, substantially as described.

In witness whereof, I have hereunto set my hand this 9th day of March 1911.

FREDERICK W. CAPPELEN.
